UNITED STATES PATENT OFFICE.

GEORGE L. HALL, OF PERKASIE, PENNSYLVANIA, ASSIGNOR TO CLOX-LITE MFG. COMPANY, INC., OF PERKASIE, PENNSYLVANIA, A CORPORATION OF DELAWARE.

DESIGN FOR A UNITARY PARKING LAMP AND MIRROR FOR VEHICLES.

60,616.

Specification for Design.

Patented Mar. 14, 1922.

Application filed January 26, 1922. Serial No. 371. Term of patent 14 years.

To all whom it may concern:

Be it known that I, GEORGE L. HALL, a citizen of the United States, residing at Perkasie, in the county of Bucks and State of Pennsylvania, have invented a new, original, and ornamental Design for a Unitary Parking Lamp and Mirror for Vehicles, of which the following is a specification, reference being had to the accompanying drawing, forming a part thereof.

Figure 1, is a perspective view of the front of a unitary parking lamp and mirror for vehicles, showing my new design, and

Figure 2, is a perspective view of the top and rear of the same.

My design includes a circular mirror having a central cleared portion through which a red light passes when the lamp is lighted.

I claim:

The ornamental design for a unitary parking lamp and mirror for vehicles as shown.

In testimony whereof I affix my signature.

GEORGE L. HALL.
